GRINDING MILL INSULATOR AND COOLER

James T. Morgan, 1020 S. 12th St.,
Allentown, Pa. 18103

Filed May 7, 1968, Ser. No. 11,811

Term of patent 14 years

Int. Cl. D15—10

U.S. Cl. D55—1

Fig. 4.

Fig. 2.

*Fig. 3.**Fig. 4.**Fig. 5.*FIG. 1 is a front elevation view of the invention;
 FIG. 2 is a top plan view;
 FIG. 3 is an end view;
 FIG. 4 is a sectional view taken along lines 4—4 of FIG. 1; and
 FIG. 5 is a sectional view taken along lines 5—5 of FIG. 2.

The dominant features of my design reside in the portion shown in full lines.

I claim:

The ornamental design for a grinding mill insulator and cooler, as shown and described.
